UNITED STATES PATENT OFFICE

2,494,189

VENTILATOR TYPE WINDOW STRUCTURE

Lewis A. Meyers, Fort Worth, Tex.

Application October 23, 1944, Serial No. 559,928

2 Claims. (Cl. 189—69)

1

This invention relates to an improved adjustable ventilating window which is especially, but not necessarily, adapted for use in conventional homes or dwellings, the same being adapted to take the place of the now commonly used double sash window constructions.

Briefly, the invention has to do with an especially constructed frame-work, preferably of metal, adapted to fit in the window opening and having, if desired, ornamental mouldings around the outer marginal edges both interiorly and exteriorly in respect to the surfaces of the building wall. This frame-work is provided with horizontal vertically spaced cross members or mullions and the latter have for their purposes to part and support the intervening transom-style glass windows. The latter are hingedly mounted on the cross members and are adapted to swing into the frame-work in a manner to rest in inwardly and upwardly inclined positions to then serve as convenient substantially draft-proof ventilators.

One phase of novelty would appear to reside in the frame-work made up of companion slidably telescoping rectangular sections, one of which may be identified as the inner section and the other as the outer section. The inner section is provided with the aforementioned cross members and the outer section is provided on its inwardly facing marginal edges with flexible tongues which are cut on the job, to proper lengths and secured to the adjacent inner marginal edge portion of the remaining section to thus join the two complementary sections releasably and operatively together.

An additional object of the invention is to provide the cross members, these of hollow polygonal form with lengthwise slots in their upper window casing portions, said slots serving as keepers for depending hinging and assembling flanges on the window-panels, that is, the marginal frame portions of said panels.

In addition, novelty is thought to reside in the provision of the coacting bevelled surfaces between the window-panel-frames and underneath surfaces of the cross members, together with resilient latch means for holding said window-panels closed and conveniently permitting movement of the latter from closed to open positions.

A further object of the invention has to do with the use of window panels or transoms each provided with a frame construction having vertical edge portions projecting outwardly to coact with complementary facilities on the vertical frame members of the relatively stationary

2

frame-work of the window opening to provide desired weather seals, thus using the frames of the window panels and fixed frame-work to coact in providing interlocking "weatherstrips."

Other objects, features and advantages, commercially, structurally and otherwise, will be evident from the drawings and the attending description of said drawings, and particular points will be set forth in the terminating portions of this specification.

In the drawings, wherein like numerals are employed to designate like parts throughout the same:

Figure 1 is a front elevation of a fragmentary portion of a building wall showing the improved multiple purpose "summer-winter" window embodied therein, said window constructed in accordance with the principles of this invention.

Figure 2 is a view, partly in section and partly in elevation, through one of the window units and upper and lower associated cross-members, or so-called mullions.

Figure 3 is a vertical section, (glass pane omitted) on the plane of the line 3—3 of Figure 2, looking in the direction of the arrows.

Figure 4 is an enlarged fragmentary view, this being a horizontal section on the line 4—4 of Figure 2, also looking in the direction of the arrows, showing the interlocking weather strips or elements on the frame-work and window panels.

Figure 5 is a central vertical sectional view through the structure seen in Figure 1, this view being on the line 5—5 and showing two of the windows "open" and two "closed."

Figure 6 is an enlarged detailed fragmentary section on the line 6—6 of Figure 5.

Figure 7 is a similar view, with portions removed, this being the structure seen opposite to that appearing in Figure 6, in serving to bring out the separable over-lapping relationship of frame-sections of the frame-work.

Figure 8 is a perspective view of one of the aforementioned mullions or cross members.

Figure 9 is a perspective view of one of the window panels or transoms per se.

Figure 10 is a perspective view of a screen which is used in summer to replace a corresponding storm window which is substituted in winter.

Figure 11 is a fragmentary detailed perspective showing one of the assembling and retaining tongues carried by one of the verticals of the outer frame-section of the twin section frame-work.

Figure 12 is a fragmentary perspective of one corner of the building, frame and windows in said frame.

Figure 13 is a fragmentary section, partly in elevation detailing the spring latch and finger controlled means therefor.

The frame-work, which is fitted into the window opening in the building wall 13, is denoted generally by the reference numeral 14. As before stated, this frame-work is preferably of metal, such as for example aluminum, and is composed of two substantially rectangular frame units or sections, these being fitted in telescoping or interfitting relationship. The inner frame section is denoted by the numeral 15 and the outer one by the numeral 16 (see for example, Figure 5). As brought out in Figure 7 the parts of the sections are shiftably mated and are adapted to be adjustable, one against the other in order to increase the width of the frame to adapt it to walls of different thicknesses. Thus, in a sense the frame-work is expandable and retractable in order to adapt itself to window openings. Various ways and means may be employed for adjoining the two sections together. In Figs. 5 and 7 we see one of the verticals of the outer section provided with size adapting tongues 17. One of these is detailed in Figure 11. The tongues are provided at desired intervals (see Fig. 5) and are bolted or otherwise fastened as at 18 to the adjacent vertical edge of the companion verticals of the complementary inner section 15. Generally speaking the frame-work is merely an extensible and retractable rectangular "box" fitted into the window opening, the complementary sections being connected by the tongues 17 and fasteners 18. At the time of manufacture, all adapter tongues 17 are made relatively long, and at the time of installation the workman clips the free ends to desired lengths, punches a bolt hole where needed, and is thus enabled to meet the frame size requirements of the job in hand. It is also my intention to provide the outer marginal edges of the respective projecting frame sections 14 and 15 with suitable finishing moldings. I have shown a fragmentary portion of one of the molding-parts as at 19 in Figure 7. A similar molding is provided on the other or outer projecting edge portion of the frame-work as indicated at 20 in Figure 6.

Reference being had to Figure 5 it will be seen that the vertical members 21 of the inner frame section 15 are provided at suitably spaced and aligned points with indentations forming supporting beads 22. These are properly positioned and inclined to serve as rests for the window panels (ranging from 4 to 5 in a complete set) 23. Each window is proportioned to be swingable completely within the outer marginal limits of the frame-work. That is to say, the windows are not of a transverse dimension to project outwardly of the surrounding frame sections when the windows are moved to inclined open position as seen in Figure 5. Before describing the windows I desire to direct attention to the vertically spaced parallel and vertically aligned cross members 24, sometimes referred to in the trade as horizontal "mullions." These are arranged in positions toward the outer marginal area of the frame-work. Each cross member is of tubular or hollow form substantially rectangular in cross-section as shown, for example, in Figure 8. The top panel basing and support-

ing wall 25 is provided with longitudinally spaced slots which serve as guides and key-ways 26 for depending hinge-flanges on the windows, said flanges indicated at 27. The vertical front wall of each cross member depends below the bottom wall 29 and is formed with a return bend or hook 28 which constitutes a weatherstrip or seal. The bottom wall of each cross member is beveled or inclined at the approximate angle indicated at 29.

The windows are set in between the respective cross members as brought out in Figure 5 serving both as closures as well as ventilators.

Each window comprises a suitable pane 30 and a rectangular marginal surrounding frame. The frame has inner and outer parallel internal flanges 31 embracing the edge portions of the pane and holding same in place. It will be noticed that the vertical end members of the surrounding frame are provided at 32 with adapter notches for reception of the end or edge portion of the weatherstrips 28 on the cross-members. These provide for close interlocking relationship as brought out for example, in Figs. 5 and 13. The protruding tapered edge 33 of the frame member 34 overlaps the hook-flange or weatherstrip 28 to provide the desired interlocking feature as shown at the top in Figure 2 and again in Fig. 13. Also, this frame member 34 is beveled to mate closely with the corresponding inclined under wall 29 of the adjacent cross member. Furthermore, the projecting vertical edges 35 (see Figure 9) function as interlocking weatherstrips or joint elements and may be slightly beveled to engage in the inbent flanges 36 struck out from the verticals of inner frame section 15 as shown in Figure 4. Consequently, we have a weather seal at the top (Fig. 2) and also seals along the vertical edges (Fig. 4). At the bottoms of the window panels the flanges 27 depending into the respective cross members by way of the keying and hinging slots 26 serve as effective weather joints.

I also contemplate using a suitable spring latch 37 (see Figs. 9 and 13), this to be provided on the top portion of each window panel and the bottom wall 29 of the cross member is apertured and thus constructed to provide a keeper seat for said latch. Obviously, any suitable means other than shown may be employed for keeping the windows closed or to facilitate opening and closing same.

Furthermore, if desired, a stop strip 38 is provided on the in frame section 15, to accommodate a screen 39 as shown in Figs. 1, 6 and 12. The screen is optional equipment and, it might be added, that in winter-time where needed, a glass storm panel (not shown) could be employed. Thus, this window is adaptable to many different functions and year round purposes.

I desire to stress some of the advantages attending an adjustable frame and ventilating window assembly of the form herein shown and described. It is estimated that its adoption and use will effect savings in labor and time in constructing as well as in installation. Likewise, there will be a savings in up-keep, there being no painting required, and very little repairing of parts. Unquestionably, it is a novel ventilating window, considered in its entirety, providing vents where needed. It is possible to open the two lower vents, or the upper two or to alternate same in any desired manner.

Expediency and ease of installation is a factor, there being no putty, no weights, no cranks

needed, and no special tools required for application and subsequent repairs.

It is easy to clean. In fact, each panel can be bodily and readily removed and quickly taken to a sink to wash both inside and outside surfaces of the glass, after which the panel or window can be readily replaced. These windows can be left open, as a general proposition, in rainy weather without allowing the rain to blow into the room. This is an important factor where storms suddenly come up and the windows have been left open. The over-all structure is comparatively weatherproof and is adaptable to the installation of a screen in summer, and a storm window in winter. The ease of removal and replacement of window panes or sashes permits replacement in case of accidental breakage.

The telescopic inner and outer sections of the main frame make possible fitting them into any casing wall ranging from 6½ to 13 inches, doing away with special order jobs. The ornamental edging moldings at inner and outer sides of the frame structure are optional but are desirable and will prove admirable finishing features.

Reviewing some of the meritorious aspects and phases of the invention it will be evident that novelty is predicated, on the other hand, on the expandable and contractable frame which lends itself adaptable to fitting properly in window openings of varying widths. This is attained by employing a frame made up of complementary and companion inner and outer rectangular sections, these having their major portions fitting in overlapping and telescopic relationship, the outer perimeter or marginal edge of the outer section projecting beyond the building wall and carrying a bordering face-molding. Likewise, the corresponding or outer perimeter edge of the inner section projects beyond the surface on the inner side of said wall, said projecting edge also carrying a marginally surrounding and bordering molding. It is appreciated that it would not be new in the art to simply provide molding equipped sections. It is to be observed therefore that the inner perimeter edge of the outer frame section is provided with a plurality of extension tongues, these tongues of indefinite lengths at the original manufacturing step. Consequently, the tongues extend through the window opening on the inside wall surface and generally beyond the coacting marginal edge of the inner frame section and they are then sheared or otherwise cut off and punctured to provide bolt holes to line up the existing bolt holes and bolts in said inner section. Hence, through the medium of these hand cut tongues it is possible to attain the desired adjustment results.

Novelty is also predicated upon the tubular cross members or mullions, these being, by preference, quadrilateral in cross section. One feature of newness resides in the elongated slots forming keyways for the tongues or flanges on the sash-like window. Another point to note is the fact that the flat front walls of each mullion extend down in a skirt-like manner and are provided with lateral inturned bends forming weather seal hooks.

The indentations forming the beads in the vertical portions of the main frame structure are of lengths sufficient to support the windows but terminate within the width area of the frame. It is important to keep in mind the fact that the rectangular windows or sashes are also proportioned in relation to the width dimensions of the surrounding frame in order that no portions of

the windows protrude beyond the front and rear marginal edge portions of said frame when the windows are swung in and down to ventilating positions.

It is believed that the structure is an expedient and practicable one and susceptible of aptly fulfilling my aims and the requirements of the manufacturer, as well as the trade in general.

It is thought that persons skilled in the art to which the invention relates will be able to obtain a clear understanding of the invention after considering the description in connection with the drawings. Therefore, a more lengthy description is regarded as unnecessary.

15 Minor changes in the shape, size and arrangement of details coming within the field of invention claimed may be resorted to in actual practice, if desired.

I claim:

20 1. In a window construction of the class described, a rectangular framework adapted to fit into a window opening, said framework embodying top, bottom, and vertical frame members and further including a plurality of vertically aligned

25 horizontally arranged cross-members mounted between the vertical members of the framework adjacent the normally outer edge of said framework, said cross-members being of hollow quadrilateral form in cross-section having inturned flanges on their bottom sides forming L-shaped

30 weatherstrips, the top walls of the respective cross-members being provided with centrally arranged longitudinal slots, the outer ends of said slots terminating inwardly of the outer transverse

35 end portions of the respective cross-members, a plurality of windows, each mounted between coacting pairs of said cross-members, each window including a pane and surrounding marginal frame, the marginal frame having a weatherstrip

40 to overlap and interlock with an adjacent one of the aforementioned L-shaped weatherstrips, said marginal frame being provided with depending flanges, said flanges being detachably and hingedly mounted in adjacent coacting slots, the vertical

45 members of the framework being provided with outwardly and downwardly inclined supporting rests for the windows, the outside marginal dimensions of the frames on said windows being such in relation to the dimensions of the framework that said windows are permitted to be swung to open positions against said supporting rests while still remaining wholly within the marginal confines of the framework.

2. In a window construction of the class shown 55 and described, a framework embodying inner and outer rectangular sections, a plurality of horizontal mullions mounted in said inner section, said mullions being vertically disposed one above the other and being situated inwardly of said

60 stop strip, each mullion having a flat top surface provided with spaced keeper and assembling slots, an outer surface provided at its bottom with an inturned flange, and an outwardly and downwardly inclined bottom surface spaced above

65 said flange, a plurality of insertable and removable window panels, said panels being located between respective pairs of said mullions, each window panel embodying a frame, said frame including, at the bottom thereof, keying and hinging

70 flanges and said flanges being fitted into the coacting slots, the upper frame member of the window panel being beveled outwardly and downwardly and corresponding to the inclination of the bottom of the coacting mullion, and said upper frame member having interlocking associa-

tion and connection with the coating inturned flange, and a plurality of diagonally disposed beads on the verticals of said inner frame section located inwardly of the mullions and lined up with the respective mullions to assist in guiding and piloting the window panes into place in relation to the mullions when the window panes have been removed for cleaning and are being replaced in the spaces between the mullions.
